UNITED STATES PATENT OFFICE.

LONNIE POWELL, OF BEAVER CROSSING, NEBRASKA.

CURRYCOMB.

SPECIFICATION forming part of Letters Patent No. 588,352, dated August 17, 1897.

Application filed August 7, 1896. Serial No. 602,035. (No model.)

To all whom it may concern:

Be it known that I, LONNIE POWELL, a citizen of the United States, residing at Beaver Crossing, in the county of Seward and State 5 of Nebraska, have invented certain new and useful Improvements in Currycombs; and I do hereby declare the following to be a full, clear, and exact description of the invention, such as will enable others skilled in the art to 10 which it appertains to make and use the same.

My invention relates to currycombs.

My object is to provide a more simple, cheap, and compact currycomb which will be of such 15 novel and improved construction that its teeth will be normally housed or protected, but will be projected for use when the comb is applied to the animal, and after removal from the latter the teeth will be automatically cleaned.

Having this object in view, my invention 20 consists of a currycomb comprising certain novel features and combinations appearing more fully hereinafter.

In the accompanying drawings, Figure 1 is a front elevation of my improved currycomb; 25 Fig. 2, a like view, but showing the teeth projected; Fig. 3, an end elevation; Fig. 4, a plan view; Fig. 5, a front elevation of a modified construction, and Fig. 6 a bottom plan view of the same.

30 The numeral 1 designates the back of my improved currycomb, and 2 is a handle suitably connected to said back.

The numerals 3 designate pin-teeth which are suitably fastened to the back and are located in parallel rows, but any other disposition of the pins can be employed.

The numeral 4 designates a cleaning-plate which is provided with a series of apertures 5 in which the ends of the pin-teeth work. At 40 each corner of the cleaning-plate there is located an upright 6, which is suitably fastened to said plate, being provided with a reduced upper portion 7, which passes loosely through the back, and 8 designates a key which passes 45 through the upper end of the reduced portion and limits the upward movement of the back, so as to prevent the pin-teeth from being pulled entirely out of the openings in the cleaning-plate.

50 The numerals 9 designate coil-springs which encircle the uprights and keep the back normally raised, so that the pin-teeth are retracted in the openings in the cleaning-plate and kept properly cleaned at all times. It 55 will be seen that the disposition of the springs

is such that they are retained in position against displacement and are not in the way of the teeth.

The device is extremely simple and compact and not liable to get out of order. 60

The operation is as follows: When the comb is applied to the animal, the pressure on the handle forces the back down against the action of the springs, thereby projecting the pin-teeth through the openings in the cleaning-plate, so that the currying operation can be properly carried on. Immediately upon the comb being removed from the animal the spring lifts the back, so that the pin-teeth are retracted in the openings and kept properly 70 housed.

Referring now to the modified construction shown in Figs. 5 and 6, in this instance in place of the rows of pin-teeth I employ a series of plates 10, provided with teeth on their 75 lower edges. For the holes or apertures in the cleaning-plate there are substituted longitudinally-extending slots 11, through which the plates 10 work.

Having now described my invention, what 80 I claim as new, and desire to secure by Letters Patent, is—

In a currycomb, the combination with a back, of a handle connected thereto, rows of teeth connected to the back, a cleaning-plate 85 having openings through which the said teeth can pass, uprights connected to said cleaning-plate and provided with reduced portions which work through openings in the back, the shoulders thus formed serving as abutments for the back to limit the movement of the same toward the cleaning-plate, pins passing through the reduced portions on the opposite side of the back from the shoulders aforesaid, and coil-springs encircling the uprights and located between the back and the cleaning-plate, the said parts being so disposed and related that the springs are adapted to keep the teeth normally housed in the openings of the cleaning-plate and the movement 90 of the back toward the cleaning-plate to project the teeth through the latter. 95

In testimony whereof I have signed this specification in the presence of two subscribing witnesses.

LONNIE POWELL.
